CHAIN SAW BLADE COVER

Evald Torokvei, 12 Alderbrook Drive,
Don Mills, Ontario, Canada

Filed Dec. 5, 1966, Ser. No. 4,911

Term of patent 14 years

(Cl. D93—3)

FIG. 1

FIG. 2

FIG. 3

FIG. 4

FIG. 5

FIG. 6

FIGURE 1 is a side elevational view of a chain saw blade cover showing my new design as attached to a chain saw shown in broken lines for illustrative purposes only;

FIGURE 2 is an enlarged side elevational view thereof;

FIGURE 3 is a top view thereof;

FIGURE 4 is a rear end elevational view thereof;

FIGURE 5 is a front end elevational view thereof; and

FIGURE 6 is a cross-sectional view as taken along the line 6—6 of FIGURE 2.

I claim:

The ornamental design for a chain saw blade cover, as shown and described.
